US00D769502S

(12) **United States Design Patent** (10) **Patent No.:** **US D769,502 S**
(45) **Date of Patent:** **** Oct. 18, 2016**

(54) **DLIGHT**

- (71) Applicant: **NORD LIGHT S.p.A.**, Pontassieve (IT)
(72) Inventor: **Jan Van Lierde**, Pontassieve (IT)
(73) Assignee: **ARTEMIDE S.p.A.**, Milan (IT)
(**) Term: **14 Years**
(21) Appl. No.: **29/498,773**
(22) Filed: **Aug. 7, 2014**

Related U.S. Application Data

- (62) Division of application No. 29/415,910, filed on Mar. 15, 2012, now Pat. No. Des. 713,585.

(30) **Foreign Application Priority Data**

(57) **CLAIM**

The ornamental design for a downlight, as shown and described.

DESCRIPTION

FIG. 1 is a bottom perspective view of a downlight showing my new design; and,

FIG. 2 is another bottom perspective view thereof.

The broken lines in FIGS. 1 and 2 represent environmental subject matter only and form no part of the claimed design.

1 Claim, 2 Drawing Sheets
